ABSTRACT

To provide a connector capable of appropriately attaching a retainer to a housing while reliably arranging a cable terminal at an appropriate position even when a clearance between members is reduced in order to reduce the size of the connector. A cable terminal 20 has a first stopped part 24a. A retainer 40 has a positioning post 41 positioned in a rearward direction from the first stopped part 24a of the cable terminal 20 and restricting movement of the cable terminal 20 in a rearward direction. The positioning post 41 is elastically deformable to move in a forward-rearward direction.

CONNECTOR, CONNECTOR ASSEMBLY, AND RETAINER

RELATED APPLICATIONS

The present application is a national phase of PCT/IB2021/054740, filed May 31, 2021 which claims priority Japanese Application No. 2020-099506, filed Jun. 8, 2020, which are incorporated herein by reference in their entireties.

TECHNICAL FIELD

The present disclosure relates to a connector to which a cable terminal is attached, a connector assembly including the connector, and a retainer used in a connector.

BACKGROUND ART

Patent Document 1 listed below discloses a connector having: a housing with a terminal storage chamber into which a cable terminal is inserted; and a retainer attached to the housing. An elastically deformable locking arm ("elastic locking piece" in Document 1) is formed in the housing. A tip end of the locking arm hooks on the cable terminal at an appropriate position in the terminal storage chamber and restricts the cable terminal from detaching. The positioning post of the retainer ("terminal locking piece" in Document 1) is provided behind a locking part of the cable terminal and restricts movement of the cable terminal in a rearward direction. In other words, detaching of the cable terminal is restricted by two sites, that is, the locking arm of the housing and the positioning post of the retainer. Furthermore, if the cable terminal is inserted into the terminal storage chamber but the cable terminal has not reached the appropriate position, in other words, if the cable terminal is partial mated with the housing, the positioning post of the retainer pushes the cable terminal to the appropriate position in the terminal storage chamber when the retainer is attached to the housing, thereby eliminating the partial mating. In this connector, clearance is ensured between members.

Prior Art Documents: Patent Documents: Patent Document 1: Japanese Unexamined Patent Application No. H06-275334.

SUMMARY

In the connector of Patent Document 1, the clearance between members is reduced if the connector is reduced in size, and therefore, the effect of dimensional tolerances of each member increases. When these dimensional tolerances accumulate, problems occur where the cable terminal cannot be positioned at an appropriate position, as well as problems where the retainer cannot be properly attached to the housing.

The connector proposed in the present disclosure includes: a cable terminal having a first stopped part: a housing having a terminal storage chamber for storing the cable terminal, a front stopper part formed in the terminal storage chamber and restricting movement of the cable terminal in a forward direction, and a part to be engaged; and a retainer including an engaging part and a positioning post provided to the rear of the first stopped part of the cable terminal, attached to a rear part of the housing by engagement of the engaging part and the part to be engaged, and that restricts movement of the cable terminal in the rearward direction. The positioning post is elastically deformable to

move in a forward-rearward direction. As a result, even when the clearance between the members is reduced, the cable terminal can be provided at an appropriate position, and the retainer can be attached to the housing.

5 A connector assembly proposed in the present disclosure is a first connector and a connector assembly that can be connected to the first connector. The second connector has a terminal and a housing holding the terminal. The first connector includes: a cable terminal having a first stopped part that connects to the second connector terminal; a housing having a terminal storage chamber for storing the cable terminal, a front stopper part formed in the terminal storage chamber and restricting movement of the cable terminal in a forward direction, and a part to be engaged; and a retainer including an engaging part and a positioning post provided to the rear of the first stopped part of the cable terminal, attached to a rear part of the housing by engagement of the engaging part and the part to be engaged, and that restricts movement of the cable terminal in the rearward direction. The positioning post is elastically deformable to move in a forward-rearward direction. As a result, even when the clearance between the members is reduced, the cable terminal can be provided at an appropriate position, and the retainer can be attached to the housing.

10 The retainer proposed in the present disclosure is a retainer that can be used in a connector having a cable terminal having a first stopped part, and a housing in which a terminal storage chamber for storing the cable terminal is formed, and where a front stopper part restricting movement

15 of the cable terminal in a forward direction is formed in the terminal storage chamber. The retainer is provided to the rear of the first stopped part of the cable terminal, and has a positioning post restricting movement of the cable terminal in a rearward direction, and an engaging part for engaging

20 with the part to be engaged of the housing. The positioning post is elastically deformable to move in a forward-rearward direction. When the retainer is attached to the housing by engaging the engaging part and the part to be engaged, and movement of the cable terminal in the terminal storage chamber in the forward direction is restricted by the front stopper part, the positioning post contacts the first stopped part and elastically deforms in the rearward direction. As a result, even when the clearance between members is reduced, the cable terminal can be positioned at an appropriate position, and the retainer can be attached to the housing.

25 The retainer proposed in the present disclosure is a retainer that can be used in a connector having a cable terminal having a first stopped part, and a housing in which a terminal storage chamber for storing the cable terminal is formed, and where a front stopper part restricting movement

30 of the cable terminal in a forward direction is formed in the terminal storage chamber. The retainer is provided to the rear of the first stopped part of the cable terminal, and has a positioning post restricting movement of the cable terminal in a rearward direction, and an engaging part for engaging

35 with the part to be engaged of the housing. The positioning post is elastically deformable to move in a forward-rearward direction. When the retainer is attached to the housing by engaging the engaging part and the part to be engaged, and movement of the cable terminal in the terminal storage chamber in the forward direction is restricted by the front stopper part, the positioning post contacts the first stopped part and elastically deforms in the rearward direction. As a result, even when the clearance between members is reduced, the cable terminal can be positioned at an appropriate position, and the retainer can be attached to the housing.

40 The retainer proposed in the present disclosure is a retainer that can be used in a connector having a cable terminal having a first stopped part, and a housing in which a terminal storage chamber for storing the cable terminal is formed, and where a front stopper part restricting movement

45 of the cable terminal in a forward direction is formed in the terminal storage chamber. The retainer is provided to the rear of the first stopped part of the cable terminal, and has a positioning post restricting movement of the cable terminal in a rearward direction, and an engaging part for engaging

BRIEF DESCRIPTION OF THE DRAWINGS

50 FIG. 1 is an exploded perspective view illustrating an example of a connector assembly containing a connector proposed in the present disclosure.

FIG. 2 is an exploded perspective view of the connector assembly.

55 FIG. 3A is a perspective view of a cable terminal.

FIG. 3B is a perspective view of the cable terminal.

FIG. 3C is a cross-sectional view of the cable terminal obtained at a cutting surface indicated by line IIIc-IIIc in FIG. 3A.

60 FIG. 3D is a plan view of a terminal front part provided by the cable terminal.

FIG. 4A is a cross-sectional view of the connector. A condition is illustrated where the cable terminal is provided at an appropriate position of the terminal storage chamber, and the retainer is attached to a housing.

65 FIG. 4B is a cross-sectional view of the connector. A process is illustrated where a cable terminal is inserted.

FIG. 5 is a side surface view of the connector in the same state as FIG. 4A. A condition is illustrated where the retainer is attached to the housing.

FIG. 6A is a perspective view of the retainer.

FIG. 6B is a side surface view of the retainer.

FIG. 7A is a rear surface view of the housing.

FIG. 7B is a cross-sectional view of the housing obtained at a cutting surface indicated by line VIIb-VIIb in FIG. 7A.

FIG. 8 is a perspective view illustrating a connector assembly according to a modified example.

DETAILED DESCRIPTION OF THE PREFERRED EMBODIMENTS

A connector proposed in the present disclosure will be described below. Hereinafter, an X1 direction and X2 direction illustrated in FIG. 1, and the like are respectively referred to as a right direction and left direction, a Y1 direction and Y2 direction are respectively referred to as a forward direction and rearward direction, and a Z1 direction and Z2 direction are respectively referred to as an upward direction and downward direction. These directions are used to describe the relative positional relationships of various parts of the connector, and do not limit orientation of the connector when attached to another device.

As illustrated in FIG. 1, a connector assembly has a connector 10 and a mating connector 90 that can be combined in a forward-rearward direction. As illustrated in FIG. 1, the connector 10 has a plurality of cable terminals 20, a housing 30 that holds the cable terminals 20, and a retainer 40 attached to the housing 30. The mating connector 90 has a plurality of terminals 91 and a housing 92 that holds the terminals 91.

The mating connector 90 has two terminals 91 arranged in the left-right direction, for example. The mating connector 90 is a connector provided on a circuit board (not illustrated), for example, and the terminal 91 may have a connecting part 91a that is connected to a conductor pattern of the circuit board at an end part thereof.

The housing 92 of the mating connector 90 may have a box-shaped mating part 92a (refer to FIG. 2) that opens toward the connector 10. A contact part of the terminal 91 is stored inside the mating part 92a. The housing 30 of the connector 10 fits inside the mating part 92a, and the plurality of cable terminals 20 respectively come into contact with the plurality of terminals 91. The housing 30 may have a locking mechanism that engages with the housing 92 of the mating connector 90. As illustrated in FIG. 2, the housing 30 has a locking lever 33, for example, as the locking mechanism. A hook formed on a front end of the locking lever 33 hooks on a part to be engaged 92b formed on an upper side of the housing 92. This restricts separation between the connector 10 and the mating connector 90.

The number of cable terminals 20 provided by the connector 10 and the number of terminals 91 provided in the mating connector 90 may also be more than two or may be one. Furthermore, the plurality of cable terminals 20 may be aligned not only in the left-right direction but also in the vertical direction. Similarly, the terminals 91 of the mating connector 90 may also be aligned not only in the left-right direction but also in the vertical direction. Furthermore, the mating connector 90 may be, for example, a connector that is attached to an end part of a cable, rather than a connector provided on a circuit board. In this case, the mating connector may be a connector provided with a housing to which the retainer of the present disclosure can be attached, and a cable terminal (refer to FIG. 8), as disclosed later.

A terminal storage chamber S (refer to FIG. 7B) for storing the cable terminal 20 is formed in the housing 30. The terminal storage chamber S passes through the housing 30 in the forward-rearward direction, and the cable terminal 20 is inserted into the terminal storage chamber S from a rear side to a front side of the housing 30. The connector 10 has two cable terminals 20 arranged in the left-right direction. The same number of terminal storage chambers S that are aligned in the left-right direction are formed in the housing 30.

A stopped part 21e (refer to FIG. 3C) described later is formed on the cable terminal 20. As illustrated in FIG. 4A, the housing 30 has a locking arm 31 at a lower portion thereof. The locking arm 31 hooks on the stopped part 21e and restricts movement of the cable terminal 20 in the rearward direction. Hereinafter, a position of the cable terminal 20 on which the locking arm 31 hooks (position of the cable terminal 20 illustrated in FIG. 4A) is referred to as an appropriate position. Furthermore, the stopped part 21e is referred to as a "second stopped part".

A stopped part 24a (refer to FIG. 3C) is formed on the cable terminal 20. In the example of the connector 10, the stopped part 24a is part of an inner edge of a hole Ha formed in the cable terminal 20. The retainer 40 has a positioning post 41 (refer to FIG. 1) extending in the forward direction. The positioning post 41 is positioned to the rear of the stopped part 24a, and restricts movement of the cable terminal 20 in the rearward direction (detaching from the appropriate position in the terminal storage chamber S). Furthermore, in a process of inserting the cable terminal 20 into the terminal storage chamber S, if the cable terminal 20 does not reach the appropriate position in the terminal storage chamber S, the positioning post 41 pushes the stopped part 24a in the forward direction when the retainer 40 is attached to the housing 30, thereby bringing the cable terminal 20 into the appropriate position. In other words, the positioning post 41 prevents partial mating between the cable terminal 20 and the housing 30. Hereinafter, the stopped part 24a is referred to as a "first stopped part". Furthermore, in the process of inserting the cable terminal 20 into the terminal storage chamber S, if the cable terminal 20 does not reach the appropriate position in the terminal storage chamber S, and the second stopped part 21e is positioned further to the rear than the stopper part 31a, the positioning post 41 contacts the first stopped part 24a and presses the cable terminal 20 in an inserting direction, and the second stopped part 21e presses the stopper part 31a down and goes over the stopper part 31a, when the retainer 40 is attached to the housing 30.

As illustrated in FIGS. 2 and 5, the housing 30 may have a part to be engaged 34. The part to be engaged 34 may be formed on left and right side surfaces of the housing 30, for example. The part to be engaged 34 may be a protruding part that protrudes from the side surface. On the other hand, the retainer 40 may have engaging parts 43 on left and right side parts thereof. As illustrated in FIG. 5, the engaging part 43 is a substantially U-shaped site in a side surface view extending toward the side surface of the housing 30, for example. When the part to be engaged 34 engages with the engaging part 43, the part to be engaged 34 is provided inside the engaging part 43 and restricts movement of the retainer 40 in the rearward direction relative to the housing 30 (for example, separation between the retainer 40 and the housing 30).

The shape of the engaging part 43 and the part to be engaged 34 is not limited to the example of the connector 10, so long as the shape of the engaging part 43 and the part to

be engaged 34 restrict separation between the housing 30 and the retainer 40. Furthermore, unlike the example of the connector 10, a protruding part is formed on the side surface of the retainer 40 as the engaging part 43, and the part to be engaged 34 may be formed on a side part of the housing 30, extending toward the retainer 40.

The cable terminal 20 will be described in detail. The cable terminal 20 is a member formed from a metal plate by press working (for example, a copper plate, an aluminum plate, or the like). Specifically, press working includes punching, bending, drawing, and the like.

As illustrated in FIG. 3A, the cable terminal 20 has: a terminal front part 21 having a front upper plate part 21a formed along a center line C1 (refer to FIG. 3C) along the forward-rearward direction; and a terminal rear part 23 having a rear upper plate part 23a formed along the center line C1.

As illustrated in FIG. 3A, the terminal front part 21 may have side plate parts 21b that descend from a right edge and left edge of the front upper plate part 21a. The front upper plate part 21a and the side plate parts 21b surround the center line C1. The cable terminal 20 may have a contact part 21c extending in the forward direction from front ends of left and right side plate parts 21b. Left and right contact parts 21c are formed so as to face each other, and may be elastically deformable such that an interval between the left and right contact parts 21c increases or decreases. The terminal 91 of the mating connector 90 is inserted between and contacts the two contact parts 21c.

The front upper plate part 21a is positioned in an upward direction from the contact parts 21c. As illustrated in FIG. 3D, in a plan view of the cable terminal 20, an entire body of the contact parts 21 may be covered by the front upper plate part 21a. Thereby, the contact part 21c can be protected by the front upper plate part 21a. As illustrated in FIG. 3C, a front end of the front upper plate part 21a is positioned further in the forward direction than a front end of the contact part 21c. Thereby, the front end of the contact part 21c can be protected by the front upper plate part 21c.

As illustrated in FIG. 3C, a front end 21h of the front upper plate part 21a is bent in the downward direction. In other words, the front end 21h of the front upper plate part 21c is bent toward the center line C1 of the cable terminal 20. When the cable terminal 20 is inserted into the terminal storage chamber S, if the front end 21h of the front upper plate part 21c collides with an edge of the terminal storage chamber S, the cable terminal 20 can be guided to an inner side of the terminal storage chamber S by inclining the front end 21h.

The cable terminal 20 has two bottom plate parts 21d that extend from lower edges of the left and right side plate parts 21b, respectively. The bottom plate part 21d is positioned on an opposite side from the front upper plate part 21a with the center line C1 interposed therebetween. The two bottom plate parts 21d may mutually overlap. Thereby, the strength of the cable terminal 20 can be increased.

As illustrated in FIG. 3C, a length W12 in the forward-rearward direction of the side plate part 21b is smaller than a length W11 in the forward-rearward direction of the front upper plate part 21a. A length W13 of the bottom plate part 21d in the forward-rearward direction is smaller than the length W12 in the forward-rearward direction of the side plate part 21b. The bottom plate part 21d is formed only at a rearmost part of the terminal front part 21 and may not be formed between the left and right contact parts 21c. By doing so, the width in the vertical direction of the front part of the cable terminal 20 can be reduced. Furthermore, since

the bottom plate part 21d is formed only at the rearmost part of the terminal front part 21, the length of the bottom plate part 21d in the forward-rearward direction is shorter than that of the front upper plate part 21a. However, because the two bottom plate parts 21d mutually overlap, the strength thereof can be maintained without reducing mechanical strength.

As illustrated in FIG. 3A, the protruding part 21g extending in the forward-rearward direction may be formed on the front upper plate part 21a of the terminal front part 21. Thereby, the strength of the front upper plate part 21a can be improved. An inner surface of the terminal storage chamber S of the housing 30 has an upper side surface facing the front upper plate part 21a of the terminal front part 21 inserted into the terminal storage chamber S. As illustrated in FIG. 7A, a recessed part 30e along the forward-rearward direction may be formed on the upper side surface of the inner surface of the terminal storage chamber S. Protruding parts 30f that relatively protrude may be formed on a right side and left side of the recessed part 30e. When the terminal front part 21 is inserted into the terminal storage chamber S, the protruding part 21g formed on the front upper plate part 21a is provided inside the recessed part 30e. By doing so, the cable terminal 20 can be prevented from being inserted into the terminal storage chamber S in an orientation in which an upper side and lower side are reversed.

The terminal rear part 23 may have cable holding parts 23b, 23d extending from a rearmost part of the rear upper plate part 23a. The cable holding parts 23b, 23d are sites formed by folding a metal plate, for example. The cable holding part 23b extends from a right side and left side of the rearmost part of the rear upper plate part 23a. The cable holding part 23d is formed in the forward direction from the cable holding part 23b and extends from the right side and the left side of the rear upper plate part 23a. The cable holding part 23b of the rearmost part is crimped to and holds an outer skin 29a of a cable 29. The outer skin 29a of the cable 29 is removed at an end part of the cable 29, and the cable holding part 23d on a front side is electrically connected to a conductive wire of the cable 29.

As illustrated in FIGS. 3A and 3C, the height of the upper surface (surface facing the Z1 direction) of the rear upper plate part 23a may be constant in an extending direction (forward-rearward direction) of the rear upper plate part 23a. Meanwhile, when the cable 29 held by the cable holding part 23b is thicker than the illustrated example, the rear upper plate part 23a may have a step 23f such that the position of a rear part of the rear upper plate part 23a is higher than the position of the front part of the rear upper plate part 23a, as indicated by the two-dot chain line in FIG. 3C. Furthermore, the cable holding part 23b may have a higher height (width in the vertical direction), as indicated by the two-dot chain line. In this case, the position of an upper part of an inclined part 22a, described later, of the cable terminal 20 is preferably higher than the rear part of the rear upper plate part 23a (upper edge of the step 23f). In other words, the position of the upper part of the inclined part 22a, described later, of the cable terminal 20 is preferably higher than a horizontal plane passing through the rear part of the rear upper plate part 23a. By doing so, the inclined part 22a can be pushed in the forward direction by the positioning post 41 of the retainer 40.

As illustrated in FIG. 3A, the cable terminal 20 may have a coupling part 22 positioned between the front upper plate part 21a and the rear upper plate part 23a. The coupling part 22 has the inclined part 22a on the upper part thereof. The inclined part 22a is inclined with respect to the center line

C1 so as to approach the center line C1 of the cable terminal 20 from the front end toward the rear end thereof.

As illustrated in FIG. 3C, the rear upper plate part 23a may extend straight along the center line C1. In other words, the rear upper plate part 23a may be parallel to the center line C1. Due to the presence of the inclined part 22a, the position of the rear upper plate part 23a is lower than that of the front upper plate part 21a. In other words, the distance between the rear upper plate part 23a and the center line C1 is less than the distance between the front upper plate part 21a and the center line C1.

As illustrated in FIG. 6A, the retainer 40 may have a post base part 42. The positioning post 41 extends in the forward direction from the post base part 42. As illustrated in FIG. 4A, the positioning post 41 may be positioned to the rear of the inclined part 22a of the cable terminal 20, and may restrict movement of the cable terminal 20 in the rearward direction (in other words, detaching from the terminal storage chamber S). By forming the inclined part 22a in the cable terminal 20 in this manner, the relative position of the positioning post 41 can be lowered with respect to the cable terminal 20.

As illustrated in FIG. 3C, a width W2 in the vertical direction of the terminal rear part 23 (height at the position of the cable holding part 23b) may be smaller than a width W1 in the vertical direction of the terminal front part 21 (height at the position of the bottom plate part 21d). Because the width W2 of the terminal rear part 23 is smaller than W1 of the terminal front part 21, the inclined part 22a can be formed on the cable terminal 20 and the position of the positioning post 41 can be lowered without lowering the position of the cable holding part 23b relative to the terminal front part 21. As a result, the height of the connector 10 can be reduced. In other words, the height of the connector 10 can be reduced by the aforementioned relationship between the widths W1 and W2, the inclined part 22a formed in the cable terminal 20, and the positioning post 41.

As illustrated in FIG. 4A, the positioning post 41 can have a first extending part 41a extending from the post base part 42 and a second extending part 41b extending in the forward direction from the first extending part 41a. The first extending part 41a may extend in the downward direction while curving or bending in the rearward direction from the post base part 42. The second extending part 41b extends linearly from a lower end of the first extending part 41a in the forward direction, and is positioned to the rear of the inclined part 22a. An entire body of a lower surface 41c of the second extending part 41b is lower than an upper surface 21i of the front upper plate part 21a. Thereby, the position of the second extending part 41b is lowered, and thus the height of the connector 10 can be reduced. The second extending part 41b and the rear upper plate part 23a of the terminal rear part 23a may be arranged in parallel.

Note that the first extending part 41a of the positioning post 41 need not be curved. In this case, the positioning post 41 may extend linearly in the forward direction from a base part thereof. Furthermore, the lower surface of the linearly extending portion thereof may be lower than the upper surface 21i of the front upper plate part 21a. As described later, curvature of the first extending part 41a in the connector 10 allows elastic deformation of the first extending part 41a. If at least the first extending part 41a is an elastically deformable structure, the first extending part 41a may be of any type, may have a bent or coil shaped spring structure, or may be formed from an elastic material.

As illustrated in FIG. 3A, the hole Ha penetrating a metal plate, which is a material of the cable terminal 20, may be

formed in a portion or all of the inclined part 22a. A front end 41e (refer to FIG. 6) of the positioning post 41 may contact an inner edge of the hole Ha and restrict movement of the cable terminal 20 in the rearward direction. More specifically, the front end 41e of the positioning post 41 may contact the front side 24a of the inner edge of the hole Ha to insert the cable terminal 20 at the appropriate position, or restrict movement of the cable terminal 20 in the rearward direction. The front side 24a of the inner edge of the hole Ha is the "first stopped part" described above.

According to this structure, a surface facing the rearward direction (surface with a height corresponding to the thickness of the metal plate) is formed on the front side 24a of the inner edge of the hole Ha. Furthermore, the front end 41e of the positioning post 41 (refer to FIG. 6A) is formed with a surface facing the forward direction. As a result, a force of the positioning post 41 pushing the cable terminal 20 in the forward direction efficiently acts on the cable terminal 20. In the example of the connector 10, the front end 41e of the positioning post 41 protrudes in the forward direction as compared to the right and left parts of the positioning post 41.

Note that in the example illustrated in FIG. 3D, the hole Ha is formed in the inclined part 22a, and the front side 24a (in other words, the first stopped part) of the inner edge of the hole Ha is positioned at a boundary between the inclined part 22a and the front upper plate part 21a. Meanwhile, the hole Ha may be formed straddling the inclined part 22a and the front upper plate part 21a. In other words, the first stopped part 24a may be positioned on the front upper plate part 21a.

In the example of the cable terminal 20, the rear side 24b of the inner edge of the hole Ha differs from the boundary between the inclined part 22a and the rear upper plate part 23a. This can prevent the front end 41e of the positioning post 41 from colliding with the rear side of the hole Ha when the positioning post 41 is inserted into the terminal storage chamber S and the front end 41e of the positioning post 41 contacts the front side 24a of the inner edge of the hole Ha. Meanwhile, the rear side 24b of the inner edge of the hole Ha may be positioned further in the rearward direction than the boundary between the inclined part 22a and the rear upper plate part 23a. Conversely, the rear side 24b of the inner edge of the hole Ha may be positioned further in the forward direction than the boundary between the inclined part 22a and the rear upper plate part 23a.

The hole Ha may not only be a hole penetrating through the metal plate, which is the material of the cable terminal 20, but may also be a recessed part having a bottom. Even in this case, the hole Ha has a front side 24a (first stopped part) of the inner edge thereof, and the front end 41e of the positioning post 41 can push the front side 24a of the inner edge.

The through hole Ha may be formed only in a portion of the inclined part 22a. In the example of the cable terminal 20, the inclined part 22a has a coupling shoulder part 22c, described later, positioned on a right side and left side of the through hole Ha. Furthermore, in the example of the cable terminal 20, the front side 24a (first stopped part) of the inner edge of the through hole Ha differs from the boundary between the inclined part 22a and the front upper plate part 21a, but may be positioned further in the rearward direction than the boundary. Furthermore, in the example of the cable terminal 20, the rear side 24b of the inner edge of the through hole Ha differs from the boundary between the inclined part 22a and the rear upper plate part 23a, but may

be positioned further in the forward direction than the boundary between the inclined part 22a and the rear upper plate part 23a.

As illustrated in FIGS. 3A and 3D, the coupling part 22 may have side parts 22b extending in the rearward direction from the left and right side plate parts 21b and connecting to the rear upper plate part 23a. The rear upper plate part 23a is curved so as to surround the center line C1, and the side parts 22b may be connected to the right part and the left part of the rear upper plate part 23a, respectively. The side part 22b can increase the strength of the inclined part 22a in which the through hole Ha is formed.

As illustrated in FIGS. 3A and 3D, the terminal front part 21 has a curved shoulder part 21f between the front upper plate part 21a and the side plate part 21b. The inclined part 22a may have a portion 22c extending in the rearward direction from the shoulder part 21f and connecting to the terminal rear part 23. Hereinafter, the portion 22c is referred to as a coupling shoulder part. The coupling shoulder part 22c is a portion of the inner edge of the hole Ha between the right edge and the side part 22b on the right side and a portion of the inner edge of the hole Ha between the left edge and the side part 22b on the left side. Due to the presence of the coupling shoulder part 22c, the size of the hole Ha in the left-right direction is suppressed, and the strength of the coupling part 22 is ensured. Furthermore, the coupling shoulder part 22c curves from an upper part of the side part 22b toward the center in the left-right direction. The curvature also contributes to increasing the strength of the coupling part 22.

Unlike the example of cable terminal 20, the coupling part 22 may not have the coupling shoulder part 22c. In other words, the right edge and the left edge of the inner edge of the through hole Ha may extend to the side part 22b of the coupling part 22.

Furthermore, the side part 22b may also be inclined with respect to the center line C1. Specifically, the side part 22b may be inclined so as to approach the center line C1 from the front end toward the rear end thereof. In other words, the coupling part 22 containing the portion 22c and the side part 22b has a substantially nozzle shape that gradually extends from the forward direction to the rearward direction thereof toward the center line C1, and has a substantially nozzle shaped configuration in which a part (lower side part in FIG. 3C) is cut out. This coupling part 22 may be formed by drawing.

As illustrated in FIG. 3C, a front part 23c of the right edge (lower edge on the right side) of the terminal rear part 23 and a front side 23c of the left edge (lower edge on the left side) of the terminal rear part 23 are connected to a lower edge 22e of the side part 22d of the coupling part 22. The front parts 23c of the left and right edges of the terminal rear part 23 extend in the forward and downward directions. Thereby, the size of the coupling part 22 in the vertical direction can be ensured, and the strength of the coupling part 22 can be ensured. Furthermore, the front part of the lower edge 22e of the coupling part 22 descends in a curved manner, and connects to a rear edge of the side plate part 21b. Thereby, the connection strength between the coupling part 22 and the side plate part 21b can be increased.

As described above, as illustrated in FIG. 3B, the cable terminal 20 may have bottom plate parts 21d that respectively extend from the lower end of the side plate part 21b and is positioned on an opposite side from the front upper plate part 21a with the center line C1 interposed therebetween. In the example of the connector 10, the terminal front part 21 may have two bottom plate parts 21d extending from

the left and right side plate parts 21b and overlapping each other. Meanwhile, the bottom plate part 21d may be formed only on one of the side plate parts 21b. The bottom plate part 21d may be connected to the side plate part 21b on an opposite side.

The locking arm 31 (refer to FIG. 4A) of the housing 30 has a stopper part 31a positioned to the rear of the bottom plate part 21d. When the cable terminal 20 is at the appropriate position in the terminal storage chamber S, the stopper part 31a is positioned to the rear of the rear edge of the bottom plate part 21d (second stopped part 21e) and restricts movement of the cable terminal 20 in the rearward direction.

The locking arm 31 is vertically movable about a base part 31b thereof. In a process in which the cable terminal 20 is inserted from the rear side to the front side of the housing 30, the locking arm 31 is pushed in the downward direction by the bottom plate part 21d of the cable terminal 20, as illustrated in FIG. 4B. Thereafter, when the bottom plate part 21d rides up over the protruding part of the locking arm 31 and the cable terminal 20 reaches the appropriate position illustrated in FIG. 4A, the locking arm 31 returns to an initial position due to an elastic force thereof. As a result, the stopper part 31a is positioned to the rear of the rear edge (second stopped part 21e) of the bottom plate part 21d.

As illustrated in FIG. 3C, the inclined part 22 is connected to the rear edge of the terminal front part 21. The bottom plate part 21d in which the second stopped part 21e is formed at the rearmost part of the terminal front part 21. Therefore, the position of the front side 24a (first stopped part) of the hole Ha formed in the inclined part 22 in the forward-rearward direction may essentially match the position of the rear edge 21e (second stopped part) of the bottom plate part 21d in the forward-rearward direction.

The retainer 40 will be described in detail. The retainer 40 has a plurality of the positioning posts 41 and the post base part 42. The post base part 42 bridges left and right wall parts 44a of the retainer 40 as illustrated in FIG. 6A. The same number of positioning posts 41 as the cable terminals 20 are connected to the post base part 42.

The positioning posts 41 may be elastically deformable to move in the forward-rearward direction. For example, the positioning post 41 may have the first extending part 41a connected to the post base part 42 and the second extending part 41b extending in the forward direction from the first extending part 41a, as illustrated in FIG. 4A. Movement of the first extending part 41a about the post base part 42 may change the position of the second extending part 41b in the forward-rearward direction. The positioning posts 41 may be elastically deformable to move in the forward-rearward direction as well as in the left-right direction. In the example of the retainer 40, movement of the first extending part 41a about the post base part 42 may change the position of the second extending part 41b in the left-right direction.

According to the retainer 40, the dimensional tolerances of a member can be absorbed by elastic deformation of the positioning post 41. As a result, the retainer 40 can be properly attached to the housing 30 and the cable terminal 20 can be reliably provided at the appropriate position. With a conventional connector, the engaging part 43 of the retainer 40 may not engage with the part to be engaged 34 of the housing 30 when the positioning post 41 presses the first stopped part 24a of the cable terminal 20 and inserts the cable terminal 20 to a foremost part of the housing 30, due to the influence of the dimensional tolerances of each part and accumulated clearance values between each part. However, in the connector 10 of the present disclosure, even when the cable terminal 20 is inserted to the foremost part

of the housing 30 and is formed at the foremost part of the housing 30, and the front end 21h of the front upper plate part 21a of the cable terminal 20 collides with the front stopper part 35 exposed in the terminal storage chamber S, the second extending part 41b moves in the rearward direction due to elastic deformation of the first extending part 41a of the retainer 40. As a result, the engaging part 43 of the retainer 40 can be engaged with the part to be engaged 34 of the housing 30. In this manner, the cable terminal 20 is reliably inserted into the foremost part (appropriate position) of the housing 30, and a clearance between the second stopped part 21e (refer to FIG. 4A) and the stopper part 31a of the locking arm 31 can be reduced. Thus, the connector can be reduced in size.

The positioning post 41 may have at least one curved or bent portion between the post base part 42 and the front end 41e of the positioning post 41. This allows elastic deformation of the positioning post 41. In the example of the connector 10, the first extending part 41a connected to the post base part 42 extends in the downward direction from the rear side of the post base part 42 while curving. The second extending part 41b extends in the forward direction from the lower end of the first extending part 41a. The second extending part 41b is formed along a straight line, for example. The second extending part 41b and the post base part 42 overlap with each other when viewed in a direction orthogonal to the extending direction of the second extending part 41b. More specifically, the second extending part 41b and the post base part 42 overlap in a plan view.

As illustrated in FIG. 4A, a thickness W8 of the first extending part 41a (curved portion) is smaller than a thickness W6 of the post base part 42. Thereby, deformation of the post base part 42 is suppressed, and deformation of the first extending part 41a is easily allowed. In the example of the retainer 40, the thickness of the second extending part 41a and the thickness of the first extending part 41a may essentially be the same.

As illustrated in FIG. 4A, a width W7 in the forward-rearward direction of the post base part 42 is greater than the thickness W6 in the vertical direction. Thereby, when the front end 41e of the positioning post 41 contacts the first stopped part 24a (edge on the front side of the hole Ha), the post base part 42 can be suppressed from being displaced in the rearward direction.

As illustrated in FIG. 4A, the position of the upper surface 42a of the post base part 42 is lower than the height of an uppermost part of the housing 30. In the example of the connector 10, the position of the upper surface 42a of the post base part 42 is lower than the uppermost part 33a of the locking arm 33. This arrangement of the post base part 42 can prevent the presence of the post base part 42 from becoming a site that increases the height of the connector 10.

As illustrated in FIG. 4A, the first extending part 41a (curved portion) extends from the rear side of the post base part 42, and the rearmost part 41f of the first extending part 41a is positioned further in the rearward direction than the rear end 42b of the post base part 42. The retainer 40 has a portion that is positioned in the right or left directions with respect to the first extending part 41a and further in the rearward direction than the rearmost part 41f of the first extending part 41a. Thereby, a space for allowing deformation of the first extending part 41a (curved portion) can be secured by this portion. In the example of connector 10, as illustrated in FIG. 2, the retainer 40 has a side wall part 45 positioned on the right and left sides of two positioning posts 41. As illustrated in FIG. 4A, the rear surface 45a of the side wall part 45 is positioned further in the rearward direction

than the rearmost part 41f of the first extending part 41a. Furthermore, the side wall part 45 overlaps with the rearmost part 41f of the first extending part 41a in a side surface view. In other words, an upper end of the rear surface 45a of the side wall part 45 is positioned further in the upward direction than the rearmost part 41f of the first extending part 41a, and a lower end of the rear surface 45a of the side wall part 45 is positioned further in the downward direction than the rearmost part 41f of the first extending part 41a. Thereby, a space for allowing deformation of the first extending part 41a (curved portion) can be secured by the rear surface 45a of the side wall part 45.

Note that unlike the example described herein, the retainer 40 may have a portion that is positioned in the upward or downward direction from the first extending part 41a and further in the rearward direction than the rearmost part 41f of the first extending part 41a. Even in this case, a space for allowing deformation of the first extending part 41a (curved portion) can be secured by this portion.

As described above, the retainer 40 may have engaging parts 43 on left and right side parts thereof. As illustrated in FIG. 6A, the engaging part 43 is a substantially U-shaped site in a side surface view extending toward the side surface of the housing 30, for example. The engaging part 43 has an upper extending part 43b and a lower extending part 43c extending in the forward direction from the side wall part 45. Furthermore, the engaging part 43 has a front part 43d formed on tip ends of the upper extending part 43b and the lower extending part 43c. The positioning posts 41 extend in the forward direction beyond a front surface of the front part 43d of the engaging part 43. As illustrated in FIG. 6B, in a side surface view of the retainer 40, the positioning post 41 is positioned between an upper surface of the engaging part 43 (upper surface of the upper extending part 43b) and a lower surface of the engaging part 43 (lower surface of the lower extending part 43c). More specifically, in a side surface view of the retainer 40, the positioning post 41 overlaps a rear surface of the front part 43d, for example, an opposing surface 43a opposite from the front surface of the part to be engaged 34. Based on this positional relationship between the positioning post 41 and the engaging part 43, when an engaging force between the engaging part 43 of the retainer 40 and the part to be engaged 34 of the housing 30 (force that pulls the retainer 40 forward) is transmitted through the positioning post 41 to the first stopped part 24a, a moment is less likely to occur with respect to the retainer 40.

As illustrated in FIG. 6A, a protruding part 41d extending in the forward direction may be formed on the second extending part 41b. In other words, a right part and left part of the upper surface of the second extending part 41b may be lower than the center. Thereby, interference can be avoided between the protruding part 30f (refer to FIG. 7A) formed on the inner surface of the terminal storage chamber S and the second extending part 41b. Furthermore, the protruding part 41d can increase the strength of the positioning post 41.

As described above, the first extending part 41a is connected to the rear side of the post base part 42 (refer to FIG. 4A). This allows the distance between the post base part 42 and the rear surface 30c of the housing 30 to be reduced. As a result, change can be reduced in the relative position of the housing 30 and the retainer 40 (for example, change in position in the left-right direction).

Note that the shape of the positioning post 41 is not limited to the example of the connector 10. For example, the first extending part 41a may linearly extend in a diagonal

downward direction. Furthermore, the second extending part 41b may extend in the forward direction from the lower end of the first extending part 41a. A curved portion may be formed in the forward direction from the post base part 42 to allow for elastic deformation.

As illustrated in FIG. 4A, the housing 30 has a front stopper part 35 that restricts movement of the cable terminal 20 in the forward direction. The front stopper part 35 may be, for example, a wall formed on the front end of the terminal storage chamber S. When the cable terminal 20 is inserted into the foremost part of the terminal storage chamber S, the front end 21h of the front upper plate part 21a of the cable terminal 20 contacts the front stopper part 35.

In a state in which the retainer 40 is attached to the housing 30 (hereinafter, referred to as a retainer attached state), the front end 41e of the positioning post 41 contacts the first stopped part 24a (in other words, the front side of the inner edge of the hole Ha). In other words, the length and initial position of the positioning post 41 are set such that, regardless of dimensional tolerances of the retainer 40, cable terminal 20, and housing 30, the front end 41e of the post 41 comes into contact with the first stopped part 24a in the retainer attached state. By doing so, the cable terminal 20 can be reliably provided at the appropriate position, and the retainer 40 can be attached to the housing 30. The retainer attached state refers to a state in which the movement of the cable terminal 20 in the forward direction is restricted by the front stopper part 35 and the engaging part 43 of the retainer 40 engages with the part to be engaged 34 of the housing 30. In the retainer attached state, there is no clearance in the forward-rearward direction between opposing surfaces 43a, 34a (refer to FIG. 5) of the engaging part 43 and the part to be engaged 34. Note that the length and initial position of the positioning post 41 may be set such that, regardless of the dimensional tolerances of the retainer 40 and the like, the front end 41e of the post 41 pushes the first stopped part 24a in the forward direction in the retainer attached state. In other words, in the retainer attached state, the front end 41e of the post 41 preferably contacts the first stopped part 24a, and the positioning post 41 is preferably elastically deformed in the rearward direction. Then, the front end 41e of the post 41 preferably pushes the first stopped part 24a in the forward direction by the elastic force of the positioning post 41.

As described above, the retainer 40 has a plurality of positioning posts 41. The length and initial position of the positioning posts 41 are set such that the front end 41e of all of the positioning posts 41 in the retainer attached state contacts the first stopped part 24a of the cable terminal 20.

The retainer 40 does not have a surface that faces in the forward direction and contacts the housing 30 in the retainer attached state, except for the front end 41e of the positioning post 41. For example, as illustrated in FIG. 4A, the front surface of the retainer 40 (specifically, the front surface 42a of the post base part 42) is separated from the rear surface 30c of the housing 30, ensuring clearance between the two. By doing so, movement of the retainer 40 in the forward direction is restricted only by the first stopped part 24a against which the front end 41e of the positioning post 41 makes contact. As a result, the cable terminal 20 can be pushed in the forward direction by the positioning post 41 until the cable terminal 20 contacts the front stopper part 35, and therefore, the cable terminal 20 can be more reliably provided at the appropriate position.

As illustrated in FIG. 4A, clearance is ensured between the second stopped part 21e (the rear edge of the bottom

plate part 21d) and the stopper part 31a of the locking arm 31. In the example of the connector 10, because the positioning post 41 is elastically deformable, the clearance between the second stopped part 21e and the stopper part 31a can be set to be small. The clearance may be the same as the thickness of the two bottom plate parts 21d, for example, or may be less than the thickness of the two bottom plate parts 21d.

As described above, because the inclined part 22 is formed in the cable terminal 20, the height of the upper surface of the terminal rear part 23 is lower than the height of the upper surface of the front upper plate part 21a. The second extending part 41b of the positioning post 41 extends linearly along the upper surface of the terminal rear part 23. The entire body of the second extending part 41b is positioned to the rear of the first stopped part 24a. In the retainer attached state, the post base part 42 is positioned to the rear of the housing 30 and is positioned in the upward direction from the rear part of the second extending part 41b.

FIG. 8 is a diagram illustrating a connector assembly according to a modified example. The connector assembly has a first connector 10A and a second connector 10B. In the example illustrated in the diagram, the structures of the connector 1 described above, specifically, the positioning post 41, an inclined part 22a of the cable terminal 20, the hole Ha, and the like are applied to the two connectors 10A and 10B. Hereinafter, differences between connectors 10A and 10B and the aforementioned connector 10 will be described. For matters not described, a structure of the connector 10 may also be applied to the two connectors 10A, 10B.

The first connector 10A has a housing 130A, a plurality of the cable terminals 20, and a retainer 140A. In the example illustrated in FIG. 8, the first connector 10A has six cable terminals 20. Similar to the housing 30 described above, a plurality of terminal storage chambers S into which the cable terminals 20 are inserted are formed in the housing 130A. A structure of the housing 130A may be the same as the housing 30 described above except for the number of the terminal storage chambers S. The retainer 140A has a plurality of positioning posts 41, similar to the retainer 40 described above. A structure of retainer 140A may be similar to the retainer 40 described above except for the number of positioning posts 41.

The second connector 10B has a housing 130B, a plurality of cable terminals 120B, and a retainer 140B. The second connector 10B has six cable terminals 120B that are inserted inside the contact part 21c (refer to FIG. 3A) of the cable terminals 20 of the first connector 10A. A plurality of terminal storage chambers into which the cable terminals 120B are inserted is formed in the housing 130B. Furthermore, the housing 130B has a box shaped mating part 130A that opens to the first connector 10A side in which the housing 130A of the first connector 10A mates to an inner side. The retainer 140B has a plurality of the positioning posts 41, similar to the retainers 40, 140A described above. Meanwhile, the cable terminal 120B has a hole formed with an inner edge to which an end part of the positioning post 41 contacts.

As described above, in the connectors 10, 10A, 10B proposed in the present disclosure, the cable terminals 20, 120B have the inclined part 22 formed between the front upper plate part 21a and the rear upper plate part 23a and inclined so as to approach the center line C1 toward the rear side. The retainer 40 has the positioning post 41 that is positioned to the rear of the inclined part 22 and restricts movement of the cable terminal 20 in the rearward direction

15

of the cable terminal 20. According to this structure, the positioning post 41 can prevent the housing 30 and the cable terminal 20 from being partially mated. Furthermore, the relative position of the positioning posts 41 with respect to the cable terminals 20 can be lowered. Note that the structures of the cable terminals 20, 120b having the inclined part 22a may be applied to a connector having a retainer in which a positioning post that is not elastically deformable is formed.

The cable terminals 20, 120B proposed in the present disclosure have the inclined part 22 formed between the front upper plate part 21a and the rear upper plate part 23a and inclined so as to approach the center line C1 toward the rear side. At least a portion of the inner edge of the hole Ha penetrating the metal plate, which is a material of the cable terminal 20, is positioned in the inclined part 22. According to this structure, the height of the positioning post 41 with regard to the inclined part 22 can be lowered. Furthermore, by applying the front end 41e of the positioning post 41 to the inner surface of the hole Ha, the force of the positioning post 41 is efficiently transmitted to the cable terminal 20.

In the connectors 10, 10A, 10B proposed in the present disclosure, the positioning post 41 is elastically deformable to move in the forward-rearward direction. According to the connector, the dimensional tolerances of a member can be absorbed by elastic deformation of the positioning posts 41. As a result, the retainer 40 can be appropriately attached to the housing 30 while reliably arranging the cable terminal 20 at the appropriate position even when the clearance between members is reduced in order to reduce the size of the connector 10. Note that the structure in which the positioning post 41 is elastically deformable may be applied to a connector in which the inclined part 22 is not formed in the cable terminal 20.

The invention claimed is:

1. A connector, comprising:

a cable terminal having a first stopped part;
a housing having a terminal storage chamber, a front stopper part in the terminal storage chamber, and a part to be engaged, the terminal storage chamber defining an open rear end through which the cable terminal is inserted in a forward direction for storage within the terminal storage chamber; and
a retainer including a positioning post and an engaging part, wherein the positioning post includes a post base part having a front end and an opposite rear end, a first extending part extending downward from the post base part and a second extending part extending linearly in the forward direction from the first extending part and terminating in a front end, wherein the first extending part is configured to elastically deform such that the second extending part is configured to move in a plane defined by the forward direction, an opposite rearward direction, a left direction and a right direction, the left and right directions being orthogonal to the forward and rearward directions, wherein the engaging part is coupled to the post base part and configured to engage with the part to be engaged of the housing, wherein the second extending part is inserted in the forward direction into the terminal storage chamber through the open rear end of the housing and is engaged with the first stopped part of the cable terminal, and the retainer is attached to the housing by engagement of the engaging part and the part to be engaged, and
wherein movement of the cable terminal in the terminal storage chamber in the forward direction is restricted by the front stopper part, and wherein the front end of

16

the second extending part contacts the first stopped part and the first extending part is configured to elastically deform to provide for movement of the first extending part only in the plane and thereby restricting movement of the cable terminal in the rearward direction when the retainer is attached to the housing by engagement of the engaging part engages with the part to be engaged.

2. The connector according to claim 1, wherein the first extending part is formed of at least one of a curved portion, a bent portion, a portion extending in a diagonal downward direction, a coil shaped spring structure, and an elastic material.

3. The connector according to claim 2, in combination with a second connector having a terminal and a housing holding the terminal.

4. The connector according to claim 1, wherein a plurality of the cable terminals are provided, wherein the retainer has a plurality of the positioning posts each corresponding to the plurality of cable terminals, and

wherein when forward movement of the plurality of cable terminals is restricted by the front stopper part, and at least one of the plurality of positioning posts is configured to contact one of the plurality of first stopped parts and is configured to elastically deform in the rearward direction.

5. The connector according to claim 4, in combination with a second connector having a terminal and a housing holding the terminal.

6. The connector according to claim 1, wherein the cable terminal has a second stopped part; the housing has a locking arm positioned to a rear of the second stopped part of the cable terminal and which is configured to restrict movement of the cable terminal in the rearward direction; and

a clearance is formed between the second stopped part and the locking arm when the positioning post contacts the first stopped part.

7. The connector according to claim 6, in combination with a second connector having a terminal and a housing holding the terminal.

8. The connector according to claim 1, in combination with a second connector having a terminal and a housing holding the terminal.

9. The connector according to claim 1, wherein the post base part extends in the forward direction and over the second extending part, and the front end of the second extending part is forward of the front end of the post base part.

10. The connector according to claim 9, in combination with a second connector having a terminal and a housing holding the terminal.

11. A retainer for use in a connector having a cable terminal having a first stopped part, and a housing having a terminal storage chamber for storing the cable terminal and a front stopper part provided in the terminal storage chamber, the retainer comprising:

a post base part having a front end and an opposite rear end;

a positioning post having a first extending part extending downward from the post base part and a second extending part extending linearly in a forward direction from the first extending part and terminating in a front end, wherein the first extending part is configured to elastically deform such that the second extending part is configured to move in a plane defined by the forward direction, an opposite rearward direction, a left direction and a right direction, the left and right directions being orthogonal to the forward and rearward directions, wherein the engaging part is coupled to the post base part and configured to engage with the part to be engaged of the housing, wherein the second extending part is inserted in the forward direction into the terminal storage chamber through the open rear end of the housing and is engaged with the first stopped part of the cable terminal, and the retainer is attached to the housing by engagement of the engaging part and the part to be engaged, and
wherein movement of the cable terminal in the terminal storage chamber in the forward direction is restricted by the front stopper part, and wherein the front end of

17

tion and a right direction, the left and right directions being orthogonal to the forward and rearward directions; and
an engaging part coupled to the post base part and configured to engage with a part to be engaged of the housing, and
wherein the positioning post is inserted into the terminal storage chamber in the forward direction and is provided rearward of the first stopped part of the cable terminal, wherein movement of the cable terminal in the terminal storage chamber in the forward direction is restricted by the front stopper part, and wherein the front end of the second extending part contacts the first stopped part and the first extending part is configured to elastically deform to provide for movement of the first extending part only in the plane and thereby restricting movement of the cable terminal in the rearward direction when the retainer is attached to the housing by engagement of the engaging part and the part to be engaged.

18

12. The retainer according to claim 11, wherein the post base part extends in the forward direction and over the second extending part, and the front end of the second extending part is forward of the front end of the post base part.

13. The retainer according to claim 12, wherein the first extending part is formed of at least one of a curved portion, a bent portion, a portion extending in a diagonal downward direction, a coil shaped spring structure, and an elastic material.

14. The retainer according to claim 11, wherein the first extending part is formed of at least one of a curved portion, a bent portion, a portion extending in a diagonal downward direction, a coil shaped spring structure, and an elastic material.

15. The retainer according to claim 11, wherein the retainer has a plurality of the positioning posts.
